PETER DE MATTIA, OF PASSAIC, NEW JERSEY, ASSIGNOR TO DE MATTIA BROTHERS, INC., OF GARFIELD, NEW JERSEY, A CORPORATION OF NEW JERSEY.

COLLAPSIBLE CORE.

Application filed October 16, 1924. Serial No. 744,045.

The present invention relates to collapsible cores employed in the manufacture of shoes or casings for pneumatic tires, and it has for its object to greatly simplify the means by which the core is operated in collapsing and expanding it and to so mount and move the key section as to provide that it may be quickly withdrawn from the position of operative continuity or from the tire and returned to that position, and also that the key section shall have such movements in collapsing the core as to provide for a maximum clearance of other movable sections in collapsing the core.

To the above ends the present invention consists of the collapsible core and the devices and combinations of devices which will be hereinafter described and claimed.

The invention is illustrated in the accompanying drawings in which

Fig. 1 shows a front elevation of the core with the sections thereof in annular form or in the plane of and position of operative continuity, as it has become known in this art.

Fig. 2 is a horizontal section taken on the line 2—2 of Fig. 1 looking downward.

Fig. 3 is a vertical section taken on the line 3—3 of Fig. 1.

Fig. 4 is a view similar to Fig. 3 and showing in full and dotted lines the movements of the key section.

Fig. 5 is a view similar to Fig. 2 taken on the line 5—5 of Fig. 1 looking downward.

Similar reference characters will be employed throughout the specification and drawing to designate corresponding parts.

The core proper comprises a plurality of segmental sections, there being four such sections in the form shown in the drawings, of which the section K is the key section, and the sections S and S¹ are pivoted sections, section F being the fixed section.

As shown in Fig. 1 the fixed section F is bolted at 5 to an ear 6 forming part of the chuck or support, and as shown in Figs. 1 and 2 the fixed section F is also bolted at 7 to the outer obliquely inclined table 8 of a bracket 9 forming part of the chuck. The ear 6 and bracket 9 are integral portions of a casting comprising a part of the chuck or support 10 which as usual is mounted on the jack or standard 12 to which it is detachably secured by means of a sliding locking bolt 11 operated by a rack and pinion

as shown in Fig. 1 in a manner which will be clearly understood by those familiar with this art.

The key section K is bolted at 14 to a shank 15 projecting inwardly therefrom radially and in the plane of the core and fitted to have a sliding movement in an open channel guide formed by parallel flanges 16 projecting from the upper surface of the casting 10 (see Figs. 1 and 2) and in which the shank 15 is arranged to have a free sliding movement radially and also to be moved into and out of said guide in a direction transverse to the plane of the core, as will be hereinafter fully described. The shank 15 also has a telescopic sliding connection with a guide 17 which is pivotally mounted at its lower end 18 on a shaft 20 disposed at right angles to the path of movement of the shank 15 mounted in hangers 21 and 22 carried by the chuck 10.

By the arrangement just described the key section K by reason of its sliding movement in the guides 16 and 17 may be moved in the plane of the core or, as it is known, the plane of operative continuity, for the purpose of moving it radially into and out of the position of operative continuity, and after it has been withdrawn from the tire in the plane of the core the swinging of the guide 17 about the shaft 20 permits the key section K to be moved in a circular path out of that plane and in a direction at right angles to that plane. Because of the location of the pivot or shaft 20 at a point adjacent the fixed section F and upon the opposite side of a line cutting the diameter of the core (as for instance the line 5—5 in Fig. 1) to that occupied by the key section K, when the guide 17 with the section K shall have been moved out of the plane of the core to the maximum extent (as indicated in dotted lines in Fig. 4) that section will be positioned out of the plane of the core and out of the path of movement of the pivoted sections.

In the construction shown in the drawing a simple toggle mechanism has been provided whereby the movement of the shank 15 of the key section K with relation to the guides 16 and 17 and with the guide 17 about the shaft 20 is effected in such time relation that the radial movements of the key section into and out of the position of operative continuity and the swinging motion thereof with relation to the plane of oper-

ative continuity are produced in operative sequence and preferably by the manipulation of a single mechanical element by the operator.

For the purpose of imparting the desired movements to the key section K there is provided a mechanism including a single actuating lever 23 offset at its upper end (as shown in Figs. 1 and 2) and pivoted at its lower end, as at 24, to the swinging guide 17, a link 25 being pivotally connected at its upper end at 26 within a slot formed in the shank 15, and at its lower end the link 25 is pivotally connected at 27 to the lever 23. This arrangement is such that with the parts in the position shown in Fig. 1 the operating mechanism is wholly within the plane of the core and a movement of the lever 23 about its pivot 24 will, through the link 25 impart a radial inward sliding movement to the shank 15 in the guides 16 and 17, thus imparting to the key section K an inward collapsing movement in the plane of the core to withdraw that section from the tire and the position of operative continuity, and this radial movement in the plane of the core will continue until the movement of the lever 23 and the link 25 approximate the position shown in full lines in Fig. 4, after which the continued movement of the lever 23 will, through the link 25, rock the guide 17 about the shaft 20, thus imparting a swinging movement to the section K out of the plane of operative continuity in a direction at right angles to that plane, the movement of the shank 15 and section K out of the plane of the core being permitted by reason of the open guides 16. This swinging movement places the parts in the dotted line position (as indicated in Fig. 4). A movement of the lever 23 in the opposite direction results first in bringing the parts into the plane of the core and thereafter moving the key section radially to the position of operative continuity (as shown in Fig. 1).

When the parts are in the position shown in Fig. 1, and as shown in Fig. 3 the pivot 27 is slightly beyond the dead center and in this position also a locking block 28, carried by the shank 15, by its upper beveled edge engages the corresponding beveled edge 29, carried by the chuck 10, the engagement of these beveled portions locking and preventing accidental displacement of the parts until movement shall be imparted thereto by means of the lever 23, thus insuring that the key section K will be held in the position of operative continuity and in the plane of operative continuity until it is desired to move it through the instrumentality of the lever 23 and the other mechanism just described. It will be observed that by the manual operation of a single instrumentality, that is to say the lever 23, the key section of the core may be first withdrawn radially

from the tire in the plane of the core, then swung outward from the plane of the core and may be restored to the position of operative continuity by the reverse movement of the lever 23 which first returns the key section K to the plane of operative continuity and thereafter moves it radially to the position of operative continuity. 70

The pivoted section S is pivotally mounted upon an inclined pivot 30 whereby that section in its movements will not only move in and out with relation to the center of the core but also in an inclined or oblique path about the pivot 30 so that it moves with relation to the plane of operative continuity 80 and out of and into that plane. The movable section S¹ is pivotally connected at 31 to a swivel, the shank 32 of which is arranged to freely turn in a bearing carried by the chuck 10. This arrangement is such 85 that the section S¹ may be withdrawn from the tire by swinging it about the pivot 31 and at the same time by the turning of the shank 32 of the swivel in its bearing the section S¹ may be moved into and out of the 90 plane of operative continuity.

The method of mounting and moving the sections S and S¹ is well known in this art and need not be further described.

In operation, and assuming the parts to be 95 in the position shown in Fig. 1 with a tire thereon the operator by grasping and pulling the lever 23 towards him withdraws the key section K radially and by a continuous movement swings said section to the position 100 shown in dotted lines in Fig. 4. Thereafter the section S will be withdrawn from the tire and moved inward swinging about the pivot 30 in the manner which has been described and thereafter the section S¹ is 105 moved inward about the pivot 31 and out of the plane of operative continuity by the turning of the swivel in its bearing.

This effectually removes the sections S, S¹ and K from the tire, and after which the 110 tire may be readily removed from the fixed section F.

Having described my invention, I claim:

1. A collapsible core comprising a plurality of core sections, a chuck or support therefor, one of said sections having a radial sliding movement on said chuck in the plane of the core, and also a swinging movement into and out of said plane, a swinging lever pivotally mounted at its lower end and a link 115 pivotally connecting said lever and said movable section, the said lever being movable from a position within the plane of the core to a position outside of said plane and transversely thereto, to impart to said movable section in succession radial movements into 120 and out of a position of operative continuity and swinging movements into and out of the plane of operative continuity. 125

2. A collapsible core comprising a plural- 130

ity of core sections, a chuck or support therefor, one of said sections having a sliding connection as well as a swinging connection with said chuck and means comprising a pivoted lever and a connecting link pivotally connected to said lever and said movable member, said lever and link movable into and out of the plane of the core and transversely thereto whereby to impart to said movable member in succession and in time relation radial movements in the plane of the core and swinging movements transversely thereto.

3. In a collapsible core comprising a plurality of movable sections, one of said sections being radially movable in the plane of

the core and also having a swinging movement into and out of the plane of the core, a sliding shank carried by said section, suitable guides therefor, one of said guides being pivoted to swing into and out of the plane of the core, a link and lever mechanism for moving said section, and complementary engaging locking members, one of which is carried by and movable with said sliding shank and the other of which is relatively fixed and arranged to be engaged by the movement of said shank to position the radially movable section in the position of operative continuity.

PETER DE MATTIA.
